(57) **CLAIM**

The ornamental design for a device for mixing fluids, as shown and described.

DESCRIPTION

FIG. 1 is a perspective view of a device for mixing fluids of the present invention;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a perspective view thereof, from the front end.
